ATT'Y

UNITED STATES PATENT OFFICE.

JULIA F. UFFORD, OF BOSTON, MASSACHUSETTS.

DESIGN FOR A TOOTH-BRUSH.

SPECIFICATION forming part of Design No. 29,219, dated August 16, 1898.

Application filed June 10, 1898. Serial No. 683,148. Term of patent 7 years.

To all whom it may concern:

Be it known that I, JULIA F. UFFORD, a citizen of the United States, residing in Boston, in the county of Suffolk and State of Massachusetts, have invented and produced a new and original Design for Brushes for Cleaning the Plates for Artificial Teeth, of which the following is a specification, reference being had to the accompanying drawings, showing a part thereof, in which—

Figure 1 is a plan view showing the back of my brush, and Fig. 2 a side elevation of the brush.

The back of the brush is substantially crescent-shaped in plan and is ornamented with parallel longitudinal lines. The handle projecting longitudinally from and integral with the back may be denominated "bird-shaped" in outline, the edges curving from said body toward each other, thence diverging or spread-

ing, thence converging again and continuing until they meet in a bill or sharp point at the end, this pointed bill-shaped end, together with the crescent-shaped back, being the leading feature of my design. The bristles projecting from the under side of the back are adjacent the inner curve of said back partly vertical and near the outer curve or edge incline at an angle to the plane of the back, so that the lower ends of the outer rows appear 25 projecting outside the vertical plane of the outer edge of said back.

What I claim is—

The design for a tooth-brush herein shown and described.

JULIA F. UFFORD.
